UNITED STATES PATENT OFFICE.

JAMES SHENNAN KIRKPATRICK, OF OTAUTAU, NEAR DUNEDIN, NEW ZEALAND.

GATE OR DOOR LATCH.

1,071,058.

Specification of Letters Patent. Patented Aug. 26, 1913.

Application filed November 11, 1912. Serial No. 730,730.

To all whom it may concern:

Be it known that I, JAMES SHENNAN KIRKPATRICK, a subject of His Majesty the King of Great Britain, residing at the town of 5 Otautau, in the Provincial District of Southland, near the city of Dunedin, in the British Dominion of New Zealand, railway station-master, have invented certain new and useful Improvements in Gate or Door Latches; and I do hereby declare that the following is a full, clear, and exact description of the invention, such as will enable others skilled in the art to which it appertains to make and use the same.

15 My object in this invention is to provide a latch that securely holds a gate or door or the like, when same is closed or slammed, for when the latter happens, most fastenings are apt to spring up and allow rebounding.

20 For my purpose I prefer a somewhat heavy latch, operating same downward, the reverse of the usual way, so that the knob has to be raised to open the latch. I insure the gate or door being kept shut by hinging 25 the catch and furnish this with a tail, so that in shutting, the catch being the lighter, rises, and the point of the latch striking on the tail of the catch, causes it to come down and keep down. Where animals are about, or 30 where needed otherwise I protect the catch from them and from the weather by providing overhanging projecting plates.

Referring to the accompanying drawing:—Figure 1 is an elevation of a gate 35 with my latch in position thereon and also an attachment for use by riders or drivers, to open same more easily. The remaining figures are details. Fig. 2 is an elevation of the latch but with the front plate removed 40 to show same better, and Fig. 3 is an end elevation of the catch with the part of the latch that engages it and showing the protecting plates dotted on said catch. Fig. 4 is a plan of Fig. 2 with a gate-rail and part 45 of a post in position, showing the fastening to same.

A is a gate for which my latch is suitable. B B are the usual posts. C is the point of the latch, beveled or sloped back in the usual 50 manner on both edges, as it does for right or left hand fastening. C¹ is a balance weight boss to which the handle C² and C³ are secured. D is the body of the latch wherein the latch is centrally pivoted. E is the hooked, horizontal, latch-engaging arm of the angular catch and E¹ is the depending

tail-piece which holds catch E down by acting as a buffer when the gate is shut. E² E³ are horizontal plates to protect the latch from weather or animals lifting the catch 60 by rubbing against it; these are not always needed. The holes F, F in the catch-plate F¹ are made oval for adjustment of the height of the said plate. For many purposes this would complete the latch, but I add an 65 attachment for easier opening comprising a lever G provided at one end with a knob G¹ and having its other end connected to the latch near weight C¹, so that by depressing knob G¹ the latch is opened. 70

It will be seen that as catch E E¹ is by far the lighter it will lift without the latch moving and the latch-end C striking the tail E¹ forms the gist of the invention.

I find in practice, no matter how hard the 75 gate is shut this device holds it securely.

In this invention any suitable sizes or materials may be adopted.

Though any form of strutting a gate may be used, the one shown renders the gate easy 80 of adjustment when needed.

Having described my invention, what I desire to claim and obtain a patent of the United States of America, is:—

1. The combination, with a latch, and a 85 body wherein said latch is pivoted; of an angular catch comprising a horizontal latch-engaging arm and a depending tail-piece, a plate to which said catch is pivoted at its apex, and a pair of protecting plates secured 90 to the first-named plate and projecting laterally directly above and below said catch, said latch being considerably heavier than said catch, whereby it will raise said latch-engaging arm on striking the same and will 95 subsequently depress said arm on striking said tail-piece.

2. The combination, with a latch having a weighted end, and a body wherein said latch is centrally pivoted; of an angular catch 100 comprising a horizontal arm adapted to engage the other end of said latch and a depending tail-piece, and a plate to which said catch is pivoted at its apex, said latch being heavier than said catch, whereby it will 105 raise said latch-engaging arm on striking the same and will subsequently depress said arm on striking said tail-piece.

3. The combination, with a latch, and a body wherein said latch is centrally pivoted; 110 of an angular catch comprising an arm adapted to engage one end of said latch and

a depending tail-piece, a plate to which said catch is pivoted at its apex; a centrally-pivoted operating lever, and a connection between the other end of said latch and the 5 adjacent end of said lever.

Dated this 12th day of September A. D. 1912.

Copies of this patent may be obtained for five cents each, by addressing the "Commissioner of Patents, Washington, D. C."

In testimony whereof, I have hereunto set my hand in the presence of two subscribing witnesses.

JAMES SHENNAN KIRKPATRICK.
